GUN WITH BARREL ADJUSTABLE IN A LATERAL DIRECTION.

1,385,153.

Specification of Letters Patent. Patented July 19, 1921.

Application filed September 4, 1920. Serial No. 408,386.

To all whom it may concern:

Be it known that I, LEOPOLD SCHMIDT, residing at Essen, Germany, a citizen of the German Republic, have invented a certain 5 new and useful Improvement in Guns with Barrels Adjustable in a Lateral Direction, (for which I have filed application in Germany, filed March 9, 1918,) of which the following is a specification.

- 10 This invention relates to gun carriages, with a gun barrel which is adjustable in a lateral direction and with a traversing gear with two operating members which are independent of each other, and of which the 15 one serves for the lateral adjustment of the sighting line, while the other is intended without influencing the traverse imparted to the sighting line by the first operating member, to vary the angle which the planes 20 passing through the sighting line and the longitudinal axis of the gun carriage at right angles to the bearing plane of the gun carriage form. The present invention relates to a construction of a gun of this kind, 25 which also insures an accurate lateral adjustment of the gun when targets have to be dealt with, which, like aircraft for example, are situated at a considerable height above the place where the gun is situated. 30 The invention will be firstly described with the aid of a diagram shown at Figure 1 of the drawings, the remaining Figs. 2 to 6 inclusive showing an example of construction, being hereafter dealt with. 35 In Fig. 1 let a denote the place where the gun is situated and b — b the path along with the aircraft taken as a target moves. Let c denote the point at which the target is situated at the instant the gun is being fired and 40 d the point which the target has reached at the end of the time of flight of the projectile. The projection of the point c on the horizontal plane passing through the point a is denoted by c^1 and the projection of the 45 point d by d^1 . By observing the movement of the target the angle may be determined without difficulty which the line of vision toward the target describes in the unit of time. 50 If the range of the target at the moment be ascertained, say, by means of a range finder and also the corresponding flight of the projectile the angle δ is thereby determined, which the straight lines a c and a d form. At the instant of firing the shot the

gun is so adjusted, that the sighting line coincides with the straight line a c and therefore the vertical plane passing through the sighting line coincides with the plane a c c^1 . If the target were stationary, and if the drift of the projectile and the influence of the wind were ignored, the vertical plane passing through the longitudinal axis of the gun barrel would also have to coincide with the plane a c c^1 . As, however, during the 60 time of flight of the projectile the target has moved toward the point d , the gun must be so adjusted that the vertical plane passing through the longitudinal axis of the gun barrel may coincide with the plane a d d^1 . The vertical planes passing through the sighting line and the longitudinal axis of the gun barrel must also describe an angle which is equal to the angle between the planes a c c^1 and a d d^1 . This angle is 70 equal to the angle δ^1 which the straight lines a c^1 and a d^1 form, that is to say, is equal to the projection of the angle δ on the plane a c d^1 .

Hitherto it has been assumed that the target is movable. The same conditions exist however in the case of a stationary target if the sighting line of the gun cannot be directed upon the point of impact itself (d) but only on an auxiliary sighting point (c) 85 located at an equal height and which is at a given lateral angular distance (δ) from the point of impact (d).

The angle (δ^1) possesses for the same values of the angle (δ) very different values 90 according as the height of the target varies. Now by the gun described, which will be more fully explained hereinafter, the problem is solved in such manner that by adjusting the sighting line of the target to the 95 angle which is to be regarded as given, the vertical plane passing through the longitudinal axis of gun barrel is automatically adjusted to the angle (δ^1) and moreover in such a way that the sighting line in this case 100 can permanently retain the direction toward the target.

The invention will be further described with reference to the accompanying drawings in which Figs. 2 to 6 show a construction of gun according to the present invention.

Fig. 2 being a side elevation of the gun,

Fig. 3 is a section on the line 3—3 of Fig. 2, looking from the left,

110

Fig. 4 is a section on the line 4—4 of Fig. 3, on a larger scale, looking from above, Fig. 5 is a top plan view of the part of the gun denoted by the arrow x in Fig. 5 3 and

Fig. 6 is a section on the line 6—6 of Fig. 3 looking from the left.

A (see Fig. 2) denotes the gun barrel, which slides in a cradle B when the gun is 10 fired, which cradle B is pivotally mounted by means of two trunnions b^1 in the gun carriage C and can be adjusted together with the gun barrel A by means of a toothed sector elevating gear B². The gun carriage C 15 can be rotated on a pedestal D by means of a pin C¹, the gun carriage being rotated about the axis of the pin C¹ at right angles to its bearing plane by means of a traversing gear with a worm E, which is mounted 20 on a shaft E¹, which is mounted in one of the side walls of the gun carriage and carries a hand wheel e² and engages with worm teeth d¹ attached to the pedestal D.

On one of the two trunnions b^1 which is 25 located on the same side as the shaft E¹, is rigidly fixed a rocking lever b^3 , which is coupled by two parallel connecting rods F to a second rocking lever G rotating about a similarly directed axis. This second rocking lever G is rigidly mounted on a shaft G¹ 30 (see Fig. 3) which is mounted in a sleeve c² carried on the gun carriage. The sleeve c² widens out on the side remote from the wall of the gun carriage into a drum-shaped 35 hollow pin c³, to which is attached in the center a continuation c⁴, which terminates in a solid pin c⁵. On the hollow pin c³, the axis of which coincides with the axis of the shaft G¹ and the continuation c⁴ is rotatably 40 mounted a composite sleeve H provided with a spherical shaped intermediate piece h¹, and reaching almost to the free end of the pin c⁵.

Upon the intermediate piece h¹ is fixed by 45 means of two coaxial pins i¹ the axis of which cuts the axis of rotation of the sleeve H at right angles at the point o, a two part ring J, which carries a sighting telescope J². In the sleeve H is mounted a self locking 50 worm K, which can be rotated by means of a hand wheel k¹ (see Figs. 2 and 6), which gears into a ring of teeth o⁶ on the hollow pin c³. By rotating the hand wheel k¹ the sleeve H can therefore be so rotated on the 55 arm formed by the sleeve c² the hollow pin c³ and the continuation c⁴ together with the pin c⁵, that the sighting line of the sighting telescope J² receives the direction corresponding to the elevation of the target. The 60 sleeve H forms therefore the carrier for the means of determining the elevation of the sighting line.

For reading off the range of the target there is provided in the part of the sleeve H, 65 which covers over the hollow pin c³, a

through aperture h² provided with a reading off edge h³ (see Fig. 5) and through which a range graduation g³ is rendered visible. This latter is arranged on the outer surface of a sector G², which is rigidly 70 mounted on the free end of the shaft G¹ coupled to one of the trunnions (b¹) and projecting into the hollow pin c³, and projects into a recess c⁷ (see Fig. 3) in the hollow pin in such a way that its outer surface, which 75 carries the graduation g³ lies flush with the outer surface of the hollow pin.

The ring J, which can be rotated relatively to the sleeve H about the axis of the pin i¹, forms the carrier of the sighting means of 80 the sighting device, which determines the traverse of the sighting line. The traverse is adjusted by means of an annular operating member M, which is rotatably mounted inside the part h¹ of the sleeve H 85 on the continuation c⁴ by means of a nonrotatable pin c⁸ connected thereto. The axis of this pin c⁸ passes through the point o and is parallel with the axis of rotation of the gun carriage C, which coincides with the 90 axis of the pin C¹.

The operating member M has a cylindrical external surface m¹, the axis of which likewise passes through the point o and it further has two flanges m² arranged at right 95 angles thereto. On the ring J are rotatably mounted two coaxial pins N, the common axis of which likewise passes through the point o and is parallel with the sighting line 100 of the telescope J². The pins N project 105 through an aperture h⁴ in the part h¹ of the sleeve H into the interior of the sleeve and are embraced on their free ends by sliding pieces P, which are guided between the flanges m² on the outer surface m¹ of the operating body M. The axis of the pins N is therefore guided in the central plane of the operating member passing through the axis 110 of the pin c⁸ at right angles to the axis of the cylindrical outer surface m¹, which will 115 be briefly termed hereinafter the guiding plane. In consequence thereof for every angular position, which the sleeve H can assume relatively to arms c² c³ c⁴ c⁵, a rotation of the operating member M about the axis of the pin c⁸ must cause a rotation of the ring J relatively to the sleeve H about the axis of the pin i¹.

The value of the angle of rotation of the ring J is thus proportioned in accordance 120 with the angular position in which the sleeve H is situated relatively to the arms c² c³ c⁴ c⁵, that is to say, according to the inclination of the sighting line of the telescope J², said value is different from the value of the angle 125 of rotation of the operating member M. One of the two pins N is rigidly connected at its outer end to a graduated disk N¹ and provided with a series of bevel wheel teeth n² which gear with a series of teeth provided 130

on the edge of the corresponding aperture h^4 . Rotation of the ring J about the axis of the pin i^3 therefore causes a rotation of the graduated disk N^1 relatively to the ring

5 J and the angle of rotation of the graduated disk N^1 is proportionally equal to the angle of rotation of the ring J .

The value of the last mentioned angle of rotation, by which the amount of traverse 10 to be imparted to the sighting telescope J^2 is measured, can therefore be read off on a graduation n^3 (see Fig. 2) arranged on the graduated disk N^1 by means of a mark (not shown in the drawing) on a rib i^3 (see 15 Figs. 2 and 6) on the ring J . If the operating member M be so adjusted, that the guiding plane determined thereby is at right angles to the axis of rotation of the sleeve H , the mark located on the rib i^3 points to 20 the zero point of the graduations n^3 , irrespective of the angular position which the sleeve H assumes relatively to the arms $c^2 c^3 c^4 c^5$.

The operating member is moved by a 25 worm gear, which consists of a toothed sector m^3 rigidly connected to the operating member and a worm Q gearing into the said sector and mounted on a shaft Q^1 carried on the continuation c^4 . On this shaft Q^1 is 30 mounted a bevel wheel q^2 (see Fig. 4). This bevel wheel gears with a ring of teeth r^1 , which is arranged on a sleeve R , which is surrounded by the sleeve H and can rotate independently thereof about the same axis. 35 The sleeve R has a member R^2 rigidly connected thereto in which are carried two bevel wheels S situated opposite each other and rotatable about the same axis, so that their axis of rotation cuts the axis of rotation of 40 the sleeve R (which coincides with the axis of the pin c^5) at right angles.

In the member R^2 are also mounted two bevel wheels T and U located opposite each other, the axes of rotation of which coincide 45 with the axis of rotation of the sleeve R and each of which engages with the two bevel wheels S . Rigidly connected to the bevel wheel T is a milled head T^1 and to the bevel wheel U a spur wheel U^1 and which spur 50 wheel U^1 engages with a toothed wheel v^1 , which is fixed on a shaft V which is mounted on the continuation c^4 and extends into the sleeve c^2 . On its end lying inside the sleeve c^2 , the shaft V carries a bevel wheel v^2 55 (see Figs. 3 and 6) which bevel wheel v^2 gears with a bevel wheel w^1 , which is mounted on one end of a shaft W carried on the sleeve c^2 and the corresponding side wall of the gun carriage C . On its other end 60 the shaft W carries a bevel wheel w^2 (see Figs. 2 and 6), which engages with a bevel wheel e^3 mounted on to the shaft E^1 of the traversing gear of the gun.

As follows from what has been above 65 stated, there is provided for the operation

of the operating member M a traversing gear m^3 , Q , Q^1 , q^2 , r^1 , R , R^2 , S , T , T^1 , U , U^1 , v^1 , V , v^2 , w^1 , W , w^2 , e^3 , E^1 , e^2 with two operating members, which are independent of each other, namely, the hand wheel T^1 and the hand wheel e^2 (see Fig. 2). Then when on the one hand the hand wheel e^2 is at rest, the bevel wheel U on the gun carriage C is also at rest as this wheel is positively connected by the gearing $U^1 v^1$, the shaft V , the gearing v^2 , w^1 , the shaft W and the gearing $w^2 e^3$ to the shaft E^1 which carries the stationary hand wheel e^2 . A rotation of the hand wheel T^1 alone by means of the returning planet wheel gear T , S , U , R^2 with the middle wheel U stationary, effects a positive rotation of the sleeve R and of the operating member M , which is always positively connected thereto by the gearings r^1 , q^2 and Q , m^3 .

On the other hand, when the hand wheel T^1 and consequently the bevel wheel T is held fast, a rotation of the hand wheel e^2 effects in addition to a rotation of the gun carriage about the axis of the pin C^1 , a rotation of the bevel wheel U positively connected to the hand wheel e^2 and consequently by means of the returning sun and planet gear U , S , T , R^2 , of which the middle wheel T is now fixed, again a positive rotation of 90 the sleeve R and of the operating member M , which is always positively connected to it.

The conditions are so selected in this case that the operating member M is rotated relatively to the continuation c^4 and consequently also relatively to the gun carriage always through the same angle but in the opposite direction to that in which the gun carriage is rotated relatively to the pedestal. The guide plane fixed at the operating member retains therefore, on the rotation of the gun carriage, always the same direction relatively to the pedestal D . The adjustment of the gun to the target assumed to be a movable one according to Fig. 1 is effected 100 preferably by a gun's crew of three of which No. 1 works the hand wheels k^1 and T^1 , No. 2 the hand wheel e^2 and No. 3 the elevating gear (B^2). Assume first that the operating member is so adjusted that the guide plane 105 determined thereby is at right angles to the axis of rotation of the sleeve H parallel with the axis of the trunnions, as shown in the drawing; the guide plane of the operating member and the sighting line of the 110 telescope J^2 , which is always parallel with it are therefore in this adjustment parallel with the plane passing at right angles to the axis of the trunnions through the longitudinal axis of the gun barrel. The reading off 115 mark arranged on the rib i^3 then always points to the zero point of the graduation n^3 irrespective of which angular position the sleeve H assumes with respect to the arms 120 $c^2 c^3 c^4 c^5$.

130

In order to impart the rough traverse to the gun, No. 1 of the crew turns the hand wheel T^1 and the No. 2 the hand wheel e^2 (see Fig. 2). In order that this may be 5 more easily understood let it be first assumed that the rotation of both the hand wheels does not take place simultaneously but the one after the other. The rotation of the hand wheel T^1 alone results, as explained more fully above, in the operating 10 member M rotating relatively to the gun carriage C and, as this latter is provisionally stationary, relatively to the pedestal also. The rotation of the member M is 15 transmitted by means of the sliding pieces P and the pins N to the ring J in such a way, that this latter rotates about the axis of the pins i^1 relatively to the sleeve H, and the sighting line of the telescope J^2 fixed on 20 the ring J will therefore likewise be traversed both relatively to the gun carriage and the pedestal D in a lateral direction.

When the ring J rotates, the bevel wheel teeth n^2 on the pin N rigidly connected to 25 the graduated disk N^1 travel over the teeth h^5 so that the graduated disk N^1 is rotated relatively to the ring J. The reading off 30 mark arranged on the rib i^3 therefore, after the sighting line has been traversed by a certain amount, no longer points to the zero point of the graduation n^3 . It is now assumed that No. 2 of the crew turns the hand wheel e^2 , while No. 1 holds the hand wheel T^1 fast in the angular position, which this 35 wheel has just arrived in. The rotation of the hand wheel e^2 alone effects as more fully explained above, on the one hand by means of the worm gear E, d^4 , a rotation of the gun carriage C about the axis of the pin C^1 and on the other hand by means of the 40 driving gear $E^1 c^3, w^2 W w^1, V^2 V v^1, U^1, U, S, T, R^2 R r^1, q^2 Q^1, Q, m^3$ a rotation of the operating member M relatively to the continuation c^4 about the axis of the pin c^8 . 45 Connected with this rotation of the operating member M, there is again a rotation of the ring J about the axis of the pin i^1 and consequently a rotation of the graduated disk relatively to the ring J. The rotation 50 of the hand wheel e^2 may take place in such a direction that the zero point of the graduation on the graduated disk N^1 approaches the reading off mark on the rib i^3 (see Figs. 2 and 6) and the rotation is continued until 55 the zero point again coincides with the zero mark.

The guide plane fixed by the operating member M and the sighting line of the sighting telescope J^2 , which is always parallel 60 therewith, are then again at right angles to the axis of rotation of the sleeve H parallel with the axis of the trunnions, that is to say, the plane passing through the longitudinal axis of the gun barrel at right angles to the axis 65 of the trunnions, is again

parallel with the guide plane of the operating member M and the sighting line.

No alteration is made in the traverse, which was imparted to the guide plane of the operating member M and the sighting line of the telescope J^2 always parallel to this plane, relatively to the pedestal D of the gun by the rotation of the hand wheel e^2 since, as above described, the gun carriage rotates with the operating member 70 in the opposite direction through the same angle. The result of the two successively effected rotations of the hand wheels T^1 and e^2 consists therefore in the fact that the sighting line and the gun carriage C are 80 traversed without alteration of their mutual angular position conjointly through a definite angle in a lateral direction.

The same result is of course attained, when the two hand wheels T^1 and e^2 are 85 rotated simultaneously and the member of the gun's crew, who rotates the hand wheel e^2 , observes that the reading off mark on the rib i^3 always points to the zero point of the graduation n^3 . By simultaneously rotating the hand wheels T^1 and e^2 any desired 90 traverse can be imparted to the sighting line and the gun carriage conjointly without alteration of the mutual angular position. 95

After the rough traverse has been imparted in the manner described, No. 1 of the gun's crew now rotating the hand wheel T^1 and the hand wheel k^1 simultaneously (see Figs. 2 and 6) and consequently by means 100 of the worm gear K c^6 (see Fig. 3) rotates the sleeve H and consequently the telescope mounted thereon about the axis of the hollow pin c^3 parallel with the axis of the trunnions, lays the sighting line on the target 105 and then follows the movement thereof by continued rotation of the hand wheels T^1 and k^1 . The sighting line then coincides with the straight line $a c$ in Fig. 1 and the guide plane of the operating member M, when the axis of the pivot pin of the gun carriage stands vertical, as is to be assumed 110 with respect to the vertical plane $a c c^1$.

As soon as the angle δ is determined in the manner hereinbefore described, No. 2 of the crew regulates the rotation of the hand wheel e^2 in such a way that the reading off 115 mark on the rib i^3 now continuously points to the graduation mark of the graduation n^3 which corresponds to the angle δ , while No. 1 of the gun crew is simultaneously keeping the sight upon the target. The 120 sighting line then continuously describes the angle δ with the plane at right angles to the axis of rotation of the sleeve H and consequently also with the vertical plane passing through the longitudinal axis 125 of the gun barrel at right angles to the axis of the trunnions. The last named plane coincides now therefore with the plane $a d d^1$ 130

(see Fig. 1) *i. e.*, it forms with the vertical plane passing through the sighting line, viz., the plane $a\ c\ c^1$, as is necessary according to the description hereinbefore given, 5 the angle δ^1 . The gun therefore receives irrespective of what height the target is at, always the exact traverse δ^1 .

Finally in order to adjust the gun to the angle of elevation corresponding to the 10 range of the target, No. 3 of the crew rocks by means of the elevating gear the gun barrel A about the axis of the trunnions b^1 until the shaft G^1 coupled to the one trunnion by the connecting rods F and the sector attached 15 thereon has reached an angular position, in which the graduation mark of the graduation g^3 (see Fig. 5), which corresponds to the range of the target is adjusted to the reading off edge h^3 of the aperture 20 h^2 provided in the sleeve H. The longitudinal axis of the gun barrel then forms with the sighting line, which for the adjustment of the gun barrel effected by the elevating gear retains the direction toward 25 the target unaltered, the attachment angle corresponding to the range of the target.

Claims.

1. A gun of the class described comprising a gun barrel, a pedestal, a carriage for said 30 gun barrel rotatably supported on said pedestal, a sighting telescope supported by said carriage, said sighting telescope being rotatable in its support, an operating member mounted on said carriage, a second operating 35 member mounted on the support for the sighting telescope, gearing for rotating said sighting telescope, a traversing gear for the gun barrel, means operatively connecting the first mentioned operating member to the traversing gear and to the sighting telescope gear, means connecting the second operating 40 member to the sighting telescope gearing whereby the gun barrel and sighting telescope may be traversed simultaneously 45 through the same angle but in opposite directions, when the second operating member is held stationary and the first operating member is rotated.

2. A gun of the class described comprising a gun barrel, a pedestal, a carriage for said gun barrel rotatably supporting the same upon the pedestal, a traversing gear interposed between said carriage and said pedestal, a sighting telescope carrier mounted 55 upon said carriage, means connecting said carrier to a trunnion of the gun to cause it to be rotated through an angle corresponding to the range elevation, means supporting said telescope upon said carrier to enable it 60 to be traversed, operating means for traversing the sighting telescope, an operating member mounted on the carriage, means connecting this operating member to the gun traversing gear of the gun and to the traversing 65 means of the sighting telescope, a second

operating member mounted upon the sighting telescope carrier, means connecting the second operating member to the sighting telescope traversing means, whereby the gun barrel may be traversed without influencing 70 the traverse imparted to the sighting device but to vary the angle which is included between the plane passing through the sighting line and the plane passing through the longitudinal axis of the gun barrel at right angles 75 to the bearing plane of the gun carriage.

3. A gun of the class described comprising a gun barrel, a pedestal, a carriage supporting said gun, said carriage being rotatably mounted upon said pedestal, a traversing 80 gear interposed between said carriage and pedestal, a sighting telescope carrier supported by said carriage, a sighting telescope rotatably mounted upon said carrier on an axis parallel with the axis of rotation of the 85 gun carriage, means for rotating the sighting telescope, an operating member mounted upon the gun carriage, means connecting this operating member to the traversing gear of the gun carriage, a differential gearing 90 supported within the sighting telescope carrier and operatively connected to the telescope rotating means, means connecting said operating member to said differential gearing, a second operating member supported 95 upon the sighting telescope carrier, means connecting this second operating member to the differential gearing whereby the sighting telescope and gun barrel may be traversed simultaneously and further the traverse imparted to the gun barrel may be corrected 100 without disturbing the traverse imparted to the sighting telescope.

4. A gun of the class described comprising a gun barrel, a pedestal, a carriage for 105 said gun barrel rotatably supported upon said pedestal, a sighting means carrier supported upon the carriage, said carrier being formed in sections, a sighting telescope, said sighting telescope being mounted upon said 110 carrier to enable it to be rotated about a vertical axis parallel with the axis of rotation of the gun carriage, means for rotating the section of the carrier supporting the telescope to correspond to the range elevation, 115 means for traversing the sighting telescope about its vertical axis, the axis of rotation of the section of the carrier and the axis of rotation of the telescope traversing means passing through the same point, a traversing 120 gear for the carriage and means operatively connecting the telescope traversing means to the traversing gear of the gun.

5. A gun of the class described comprising a gun barrel, a pedestal, a carriage for said 125 gun barrel rotatably supported upon said pedestal, a sighting telescope carrier supported upon the carriage, a sighting telescope mounted upon said carrier and upon an axis which is parallel with the axis of ro- 130

- tation of the gun carriage, an operating member for rotating the sighting telescope, a sun and planet gear supported within the sighting means carrier and connected to the 5 operating member of the sighting telescope, a traversing gear disposed between said pedestal and gun carriage, an operating member for said traversing gear, means connecting said operating member to the sun and planet gear and a graduated disk connected to the 10 planet gear, a second operating member supported upon the sighting means carrier, means operatively connecting this second operating member to the sun and planet gear and a graduated disk connected to the 15 rotating means of the sighting telescope for determining the degree of traverse imparted thereto.
6. A gun of the class described comprising a gun barrel adjustable in a lateral direction, and a sighting device in combination with a traversing gear provided with two operating members, means operatively connecting one of said operating members with the sighting device for imparting thereto a lateral adjustment and means operatively connecting the other operating member to the gun barrel and sighting device, a sun and planet gear interposed between the operating members and the sighting device, whereby the gun barrel may be traversed without influencing the traverse imparted to the sighting device but to vary the angle which is included between the plane passing through the sighting line and 30 the plane passing through the longitudinal axis of the gun barrel at right angles to the bearing plane of the gun carriage.
7. A gun of the class described comprising a gun barrel, a gun carriage, a sighting device, a carrier for the sighting device, in combination with a traversing gear embodying two operating members, means connecting one of said operating members to the sighting device, means connecting the 40 other of said operating members to the sighting device, said latter operating member also connected with gearing for traversing the gun barrel, the connection between said sighting device and said operating members including a sun and planet gear, whereby when one of said operating members is driven and the other operating member held stationary, the sighting device and gun barrel will be moved through the 50 same angle but in opposite directions.
8. A gun of the class described comprising a gun barrel, a pedestal, a carriage for said gun barrel rotatably supported by said pedestal, a traversing gear for said carriage, 60 a sighting means carrier supported by said carriage, said sighting means carrier being rotatable on its support for lateral adjustment, means for rotating said sighting means carrier, said rotating means comprising an adjusting member rotatable with the 65 carriage relatively to the pedestal and relatively to the carriage about an axis having the same direction as the axis of rotation of the carriage, a gearing for rotating said adjusting member, said gearing having two 70 operating members movable independently of each other, and means operatively connecting one of said operating members to the traversing gear, whereby the carriage and said adjusting member may be traversed simultaneously through the same angle but in opposite direction, when said last-named operating member is operated and the other is held stationary.
9. A gun of the class described comprising a gun barrel, a pedestal, a carriage for said gun barrel rotatably supported by said pedestal, two trunnions rotatably supporting the gun barrel in said carriage, a traversing gear for said carriage, a sighting means carrier, a support for said sighting means carrier, the sighting means carrier being rotatable on its support for lateral adjustment and the support being rotatable relatively to said carriage about an axis 80 having the same direction as the axis of said trunnions, means for rotating said sighting means carrier relatively to its support, said rotating means comprising an adjusting member rotatable with the carriage relatively to the pedestal and relatively to the carriage about an axis 85 having the same direction as the axis of said trunnions, means for rotating said sighting means carrier relatively to its support, said rotating means comprising an adjusting member rotatable with the carriage relatively to the pedestal and relatively to the carriage about an axis 90 having the same direction as the axis of said trunnions, means for rotating said sighting means carrier relatively to its support, said rotating means comprising an adjusting member rotatable with the carriage relatively to the pedestal and relatively to the carriage about an axis 95 having the same direction as the axis of said trunnions, means for rotating said sighting means carrier, a gearing for rotating said adjusting member, said gearing having two operating members movable independently of each other, and means operatively connecting one of said operating members to the traversing gear, whereby the carriage and said adjusting member may be traversed simultaneously through the same angle but in opposite direction when said last-named operating member is operated and the other is held stationary.
10. A gun of the class described comprising a gun barrel, a pedestal, a carriage for said gun barrel rotatably supported by said pedestal, two trunnions rotatably supporting the gun barrel in said carriage, a traversing gear for said carriage, a sighting means carrier, a support for said sighting means carrier, the sighting means carrier being rotatable on its support for lateral adjustment and the support being rotatable relatively to said carriage about an axis 105 having the same direction as the axis of said trunnions and intersecting the axis of rotation of said sighting means carrier, means for rotating said sighting means carrier relatively to its support, said rotating means comprising an adjusting member rotatable with the carriage relatively to the pedestal and relatively to the carriage about an axis 110 having the same direction as the axis of said trunnions and intersecting the axis of rotation of said sighting means carrier, means for rotating said sighting means carrier relatively to its support, said rotating means comprising an adjusting member rotatable with the carriage relatively to the pedestal and relatively to the carriage about an axis 115 having the same direction as the axis of said trunnions and intersecting the axis of rotation of said sighting means carrier, means for rotating said sighting means carrier relatively to its support, said rotating means comprising an adjusting member rotatable with the carriage relatively to the pedestal and relatively to the carriage about an axis 120 having the same direction as the axis of said trunnions and intersecting the axis of rotation of said sighting means carrier, means for rotating said sighting means carrier relatively to its support, said rotating means comprising an adjusting member rotatable with the carriage relatively to the pedestal and relatively to the carriage about an axis 125 having the same direction as the axis of said trunnions and intersecting the axis of rotation of said sighting means carrier, means for rotating said sighting means carrier relatively to its support, said rotating means comprising an adjusting member rotatable with the carriage relatively to the pedestal and relatively to the carriage about an axis 130 having the same direction as the axis of said trunnions and intersecting the axis of rotation of said sighting means carrier.

an axis passing through the point of intersection of the axis of rotation of said sighting means carrier and the support appertaining thereto and having the same direction as the axis of rotation of the carriage and a universal joint coupling between said adjusting member and the sighting means carrier, a gearing for rotating said adjusting member, said gearing having two operating members movable independently of each other, and means operatively connecting one of said operating members to the traversing gear, whereby the carriage and said adjusting member may be traversed simultaneously through the same angle but in opposite direction, when said last-named operating member is operated and the other is held stationary.

11. A gun of the class described comprising a gun barrel, a pedestal, a carriage for said gun barrel rotatably supported by said pedestal, two trunnions rotatably supporting the gun barrel in said carriage, a traversing gear for said carriage, a sighting means carrier, a support for said sighting means carrier, the sighting means carrier being rotatable on its support for lateral adjustment and the support being rotatable relatively to said carriage about an axis having the same direction as the axis of said trunnions and intersecting the axis of rotation of said sighting means carrier, means for rotating said sighting means carrier relatively to its support, said rotating

means comprising an adjusting member rotatable with the carriage relatively to the pedestal and relatively to the carriage about an axis passing through the point of intersection of the axis of rotation of said sighting means carrier and the support appertaining thereto and having the same direction as the axis of rotation of the carriage and a universal joint coupling between said adjusting member and the sighting means carrier having a journal rotatably mounted on said sighting means carrier, a dial fixed on said journal for indicating the angle of lateral adjustment of the sighting means carrier, means positively connecting said journal to the sighting means carrier with respect to the lateral adjustment thereof, a gearing for rotating said adjusting member, said gearing having two operating members movable independently of each other, and means operatively connecting one of said operating members to the traversing gear, whereby the carriage and said adjusting member may be traversed simultaneously through the same angle but in opposite direction, when said last-named operating member is operated and the other is held stationary.

The foregoing specification signed at Essen, Germany, this 2nd day of June, 1920.

LEOPOLD SCHMIDT.
